US0D1077646S

(12) **United States Design Patent** (10) **Patent No.:** **US D1,077,646 S**
(45) **Date of Patent:** **** Jun. 3, 2025**

(54) **STORAGE TRAY**

(71) Applicant: **Liangliang Zhang**, Hebei (CN)

(72) Inventor: **Liangliang Zhang**, Hebei (CN)

(**) Term: **15 Years**

(21) Appl. No.: **29/977,669**

(22) Filed: **Dec. 10, 2024**

(51) **LOC (15) Cl.** **30-10**

(52) **U.S. Cl.**

USPC **D30/158**; D30/199; D28/73; D3/205

(58) **Field of Classification Search**

USPC D9/414, 420, 434, 500, 503, 504, 516, D9/517, 520, 529, 537, 540, 549, 572, D9/575, 600, 601, 607, 609, 611, 715, D9/716, 737, 738-740, 744, 755, 767, D9/772, 779, 780, 903; D7/396.1, 500, D7/502, 509-511, 513-516, 519, 550.1, D7/551.1, 551.3, 552.1, 552.2, 553.1, D7/553.3-553.5, 553.7, 553.8, 554.4, 555, D7/556, 558, 559, 331, 601, 602, 604, D7/605, 608, 612, 629, 703; D3/201, D3/202, 270, 304, 310, 313, 205; D19/80, 82.97; D28/6, 79, 73; D21/350, D21/470; D24/227; D6/515, 674, 684, D6/707.16; D30/158, 199; D8/71

(57) **CLAIM**

The ornamental design for a storage tray, as shown and described.

DESCRIPTION

FIG. 1 is a front, right and bottom perspective view of a storage tray, showing my new design;

FIG. 2 is a rear, left and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures depict portions of the storage tray that form no part of the claimed design.

1 Claim, 8 Drawing Sheets
